UNITED STATES PATENT OFFICE.

WILLIAM EXCELL BAKER, OF ALDERSHOT, ENGLAND.

WASHING-MACHINE.

SPECIFICATION forming part of Letters Patent No. 550,672, dated December 3, 1895.

Application filed March 23, 1895. Serial No. 542,946. (No model.) Patented in England November 20, 1893, No. 22,145, and January 13, 1894, No. 770.

To all whom it may concern:

Be it known that I, WILLIAM EXCELL BAKER, laundry manager, a subject of the Queen of Great Britain, residing at Fairview, 5 Redan Hill, Aldershot, England, have invented certain new and useful Improvements in Washing-Machines, (for which I have received Letters Patent in Great Britain, No. 22,145, dated November 20, 1893, and No. 770, 10 dated January 13, 1894,) of which the following is a specification.

My invention has for its object improvements in washing-machines. For this purpose I construct a washing-machine of an inner cylinder or receptacle and an outer cylinder or casing, the inner cylinder being capable of revolving in bearings and being caused to rotate and reverse by suitable gearing. Upon the outside of the ends of such inner cylinder or near thereto I cast or fix blades after the manner of air or water propellers, so that as these revolve with (or upon the same axis as) the inner cylinder the water contained in the outer casing will be carried or forced by such 25 propelling-blades through perforations or suitable openings formed in the ends of such inner cylinder and into the clothes contained therein, and I also assist the circulation by screw or helical ribs upon the outer surface 30 of the inner cylinder. I do not claim the latter generally under the present application, as they form the subject of a separate application filed simultaneously herewith, Serial No. 542,945.

35 In the accompanying drawings, Figure 1 shows a longitudinal central section through the outer cylinder, the inner cylinder being shown in side elevation. Fig. 2 shows an end view of the inner cylinder. Fig. 3 shows a 40 longitudinal central section of one end of the inner cylinder.

45 *a* is the inner cylinder, *A* the outer cylinder, and *B* bearings in the latter. The casing of the inner cylinder is bolted to the rim *b*, which is cast in one piece with the blades *c*, forming the spokes, and the hub *d*.

e is a perforated sheet of metal held between

the end of the casing *a* and the blades *c*. As shown, the surfaces of the blades *c* are inclined to the axis of the drum, their edges *c' c'* being 5° at right angles to it, while their edges *c² c²* make an acute angle with it. Other methods of fixing the blades *c* may be adopted.

f f are ribs fixed on the outside of the cylinder. In washing-machines in which the outer as well as the inner cylinder is caused to rotate these ribs may be fixed to the inner surface of the outer cylinder, as shown in Fig. 1.

It is preferred that the inner cylinder should have a central transverse partition, as has before been proposed in other machines and as indicated in dotted lines *x* in Fig. 1. The inner cylinder, it will be observed, is perforated on its periphery, and is also open at each end. 60 Propelling-blades may be employed at both ends of the cylinder or at one end only. When two sets of blades are employed, one will act to propel the liquid into the cylinder while the other acts as an exhaust. The helical or screw 65 ribs cause the liquid to pass from one end of the cylinder toward the other and assist the blades in keeping up a circulation through and around the cylinder.

What I claim is—

75 1. In a washing machine the combination of an outer cylinder, an inner cylinder, an axle connecting the inner with the outer cylinder, propelling blades *c* revolving with or upon the axle and ribs *f*, between the outer and inner cylinders, substantially as described.

2. The combination of the outer perforated cylinder, the inner cylinder open at each end and perforated on its periphery, helical ribs arranged on the periphery of the inner cylinder and propeller blades revolving with the inner cylinder and co-operating with the ribs thereof to cause a circulation around and through the cylinder and the material to be cleansed contained therein.

WILLIAM EXCELL BAKER.

Witnesses:

ROBT. L. BATEMAN,
GEORGE GREENWOOD.

It is hereby certified that in Letters Patent No. 550,672, granted December 3, 1895, upon the application of William Excell Baker, of Aldershot, England, for an improvement in "Washing-Machines," errors appear in the printed specification requiring the following corrections, viz.: In line 82, the word "perforated," at the end of the line should be stricken out and the same inserted after the word "inner" in line 83, same page; and that the said Letters Patent should be read with these corrections therein that the same may conform to the record of the case in the Patent Office.

Signed, countersigned, and sealed this 27th day of October, A. D., 1896.

[SEAL.]

JNO. M. REYNOLDS,
Assistant Secretary of the Interior.

Countersigned:

JOHN S. SEYMOUR,
Commissioner of Patents.
